UNITED STATES PATENT OFFICE.

HENRY A. DAVIS, OF LOWELL, MASSACHUSETTS.

MACHINE FOR CLEANING AND SEPARATING COTTON WASTE, &c.

SPECIFICATION forming part of Letters Patent No. 359,851, dated March 22, 1887.

Application filed October 9, 1886. Serial No. 215,766. (No model.)

To all whom it may concern:

Be it known that I, HENRY A. DAVIS, a citizen of the United States, residing at Lowell, in the county of Middlesex and State of Massachusetts, have invented certain new and useful Improvements in Machines for Cleaning and Separating Cotton Waste and other Fibrous Materials, of which the following is a specification.

10 My invention relates to the application of a revolving shaft near the beater of a waste-picker in such a manner that pieces of yarn or thread which may be mixed with unspun fiber will become wound upon the said shaft, and thereby be separated from the fiber, which is suitable to pass to the carding process, and also to certain improvements in the construction of beaters for this class of machines, whereby beaters of greater strength and increased facilities for threads to become wound upon the shaft of the beater are secured.

15 Taken together, these improvements constitute an improved machine for separating unspun fibrous material from pieces of waste yarn or thread which are too hard twisted to be advantageously carded and respun.

20 In the drawings, Figure 1 is a plan or top view of my improved machine. Fig. 2 is a side elevation of the same. Fig. 3 is an elevation of part of one end of the machine, showing the driving-pulley. Fig. 4 is a vertical cross-section of the part of the machine containing the beaters and thread-extracting shaft. Fig. 5 is a plan view of the beaters and the 25 thread-extracting shaft removed from but lying in the same relative position as when in the machine; and Fig. 6 is an enlarged view of a piece broken from the middle of the thread-extracting shaft.

30 A is the hinged covering or bonnet over the beaters, having a web or rim, a, which forms a trough to hold a supply of material, which is fed to the beaters through the inlet or feeding-opening a'.

35 B is the lower portion of the casing of the machine, to which the bonnet A is hinged by the hinges b b, and in which, below the beaters, is placed the grid or screen b', and below which there may be a dust-closet. An opening or 40 spout, b', is provided for the exit or delivery of the cleaned fiber. These parts being prin-

cipally old and well known, I do not think a detailed description of their operation necessary.

C is a shaft supported by and having its bearings in the brackets c c and c', and driven by the pulley c'. The said shaft C is designed to assist in extracting broken bits of thread, and may be a plain shaft, or roughened by cutting a fine screw-thread and one or more longitudinal grooves, c', as shown at Fig. 6. 60

In the heads of the bonnet A are slots a', to allow the bonnet to be lifted, and which are covered by the brackets c c when the cover is shut down over the beater. It will readily be seen that the thread-extracting shaft C may be 65 employed in combination with any other form of beater, scutcher, or toothed cylinder than that shown in the drawings.

When cotton containing pieces of thread is thrown against the shaft C by the beater, 70 threads will be caught and wound upon the said shaft, while if bunches of cotton should adhere with the threads they will be quickly knocked off by the action of the beater or toothed cylinder, and by stopping the machine 75 with which this device is connected the threads which have thus been picked from the cotton may be cut and stripped from the shaft. In operating the machine represented in the drawings the machine is stopped from time to time 80 and the cover A turned back, and the yarn which has become entangled upon the shaft C, and also that which has accumulated on the beater-shafts, is removed. D D' designate the beaters, each consisting of a shaft with arms 85 d d, projecting from the shaft in different radial directions and cast solid therewith. I have preferred to arrange the arms d d in spiral lines on opposite sides of the shaft, as shown in the drawings, thereby rendering the strain on the 90 shafts when in operation nearly uniform. Fan-blades d' d' also project from the beater-shaft, and are preferably cast with the same. It is not so essential, however, that the fan-blades should be of the same entire piece of metal as 95 the rest of the beater.

The beaters run in suitable bearings, d', and are driven by the pulleys d' and d', the dotted line e representing the belt which transmits power to the said pulleys, and also to the 100 pulley c'.

E represents an angle-piece, in construction

a bar of angle-iron, or a triangular strip, which is fastened within the casing for the purpose of deflecting the cotton as it is tossed about by the beaters toward the shafts, so that threads 5 may be caught and wound upon them.

Heredofore cotton waste which contains pieces of yarn or thread has been separated or the threads extracted from the unspun fiber by passing it through a machine commonly 10 known as the "Van Winkle opener," (see patents to J. E. Van Winkle, No. 38,794, June 2, 1863, reissue No. 3,363, and No. 299,297, May 27, 1884,) or similar machine having beaters 15 consisting of shafts upon which a series of radial arm castings are fastened by a hub and set-screw, or having the beater-shaft drilled and graduated radial arms inserted; and when operating the same it is necessary to occasionally stop the machine and cut or strip off from the 20 beater-shafts the threads which have become wound thereon.

To enable the beater-shaft to catch and retain short threads, it must necessarily be small in diameter, and cannot be drilled for the insertion of 25 radial arms of suitable strength without lessening the strength of the shaft. Radial-arm castings with hubs cover up a large part of the beater-shaft which might otherwise be presented to the material operated upon.

30 By making the beater of a single piece of metal, preferably a steel or bronze casting, I am enabled to make the shaft small in diameter, with radial arms projecting therefrom,

which do not weaken the shaft or materially obstruct its surface, thereby securing a shaft 35 better adapted to catch and retain threads than has heretofore been used, and it will therefore be seen that the beaters east entire are an important improvement even when used without the shaft C or the deflecting-plate E. 40

By the use of one or more plain revolving shafts located at a suitable distance from the beater I am able to catch and extract from the waste operated upon threads which would otherwise be liable to pass through the machine without being picked out. 45

Having thus fully described my invention, I claim as new, and desire to secure by Letters Patent—

1. In a picker or opener for fibrous materials, 50 the combination, with a casing provided with feeding and delivery openings, of a rotary beater having radial arms cast solid with and projecting from the opposite sides of the shaft of the said beater, substantially as herein described.

2. In a picker or opener for fibrous materials, 55 the combination, with a rotary beater and its casing, of the shaft C, revolving within the said casing near the periphery of the said beater, for the purpose herein set forth.

HENRY A. DAVIS.
